DESIGN FOR A TOY BUILDING BLOCK

Castro M. Dabrohua, Winnetka, Ill.

Original application March 12, 1945, Serial No. 118,428. Divided and this application July 26, 1945, Serial No. 120,968

Term of patent 14 years

(Cl. D34—15)

To all whom it may concern:

Be it known that I, Castro M. Dabrohua, a citizen of the United States, residing at Winnetka, in the county of Cook and State of Illinois, have invented a new, original, and ornamental Design for Toy Building Block, of which the following is a specification, reference being had to the accompanying drawing, forming a part thereof.

In the drawing:

Figure 1 is a top plan view of a toy building block, showing my new design; and

Figure 2 is a front elevational view thereof. The reverse side of the toy building block is the same as the side that is shown in Figure 2. This application is a division of design patent application Serial No. D-118,428, filed by me on March 12, 1945.

I claim:

The ornamental design for a toy building block, substantially as shown and described.

CASTRO M. DABROHUA.
